UNITED STATES PATENT OFFICE

165,902

MAN'S SHORTS OR SIMILAR ARTICLE

Simon H. Brenner, Wooster, Ohio

Application October 29, 1951, Serial No. 17,159

Term of patent 14 years

(Cl. D3—17)

To all whom it may concern:

Be it known that I, Simon H. Brenner, a citizen of the United States, residing at Wooster, in the county of Wayne and State of Ohio, have invented a new, original, and ornamental Design for Man's Shorts or Similar Article, of which the following is a specification, reference being had to the accompanying drawing, forming part thereof.

Figure 1 is a rear elevational view of man's shorts or similar article, showing my new design; Figure 2 is a side elevational view thereof; and Figure 3 is a front elevational view thereof.

I claim:

The ornamental design for man's shorts or similar article, substantially as shown.

SIMON H. BRENNER.
